US0D1082144S

(12) **United States Design Patent** (10) Patent No.: **US D1,082,144 S**
An (45) Date of Patent: ** Jul. 1, 2025

(54) **DEPILATORY APPARATUS**

(71) Applicant: **Shenzhen Ishine Technology Co., Ltd.**,
Shenzhen (CN)

(72) Inventor: **Chaoxui An**, Guangdong (CN)

(**) Term: **15 Years**

(21) Appl. No.: **35/522,035**

(22) Filed: **Jul. 19, 2024**

(80) **Hague Agreement Data**

Int. Filing Date: **Jul. 19, 2024**

Int. Reg. No.: **DM/239297**

Int. Reg. Date: **Jul. 19, 2024**

Int. Reg. Pub. Date: **Aug. 23, 2024**

(30) **Foreign Application Priority Data**

Jan. 25, 2024 (CN) 202430050981.5

(51) **LOC (15) Cl.** **28-03**

(52) **U.S. Cl.**

USPC **D28/44.1; D24/209**

(58) **Field of Classification Search**

USPC D28/44.1; D24/209

CPC A61B 18/18; A61B 2018/00476; A45D
26/0042-0052; A45D 26/0057-0061;
A61N 5/0617

See application file for complete search history.

(57) **CLAIM**

The ornamental design for depilatory apparatus as shown and described.

DESCRIPTION

1. Depilatory apparatus

1.1 : Perspective

1.2 : Front

1.3 : Back

1.4 : Top

1.5 : Bottom

1.6 : Left

1.7 : Right

Used for depilation.
